(Cl. D34—15)

To all whom it may concern:

Be it known that I, Philip F. Raeth, a citizen of the United States, residing at Evanston, in the county of Cook and State of Illinois, have invented a new, original, and ornamental Design for a Soap Bubble Blower, of which the following is a specification, reference being had to the accompanying drawing forming a part thereof.

Figure 1 is an elevational view of a soap bubble blower showing my new design;

Figure 2 is a plan view of the soap bubble blower of Figure 1; and

Figure 3 is a perspective view thereof.

I claim:

The ornamental design for a soap bubble blower, substantially as shown.

PHILIP F. RAETH.
